US00D696223S

(12) **United States Design Patent**
Will et al.

(10) **Patent No.:** US D696,223 S
(45) **Date of Patent:** ** Dec. 24, 2013

(54) **ALERTING DEVICE**

(71) Applicants: **Travis E. Will**, Renton, WA (US);
Russell E. VanDevanter, Seattle, WA (US); **Steven M. Myhre**, Seattle, WA (US); **Michael J. Myhre**, Monroe, WA (US)

(72) Inventors: **Travis E. Will**, Renton, WA (US);
Russell E. VanDevanter, Seattle, WA (US); **Steven M. Myhre**, Seattle, WA (US); **Michael J. Myhre**, Monroe, WA (US)

(**) Term: **14 Years**

(21) Appl. No.: **29/466,495**

(22) Filed: **Sep. 9, 2013**
